MUSIC PRINTING MACHINE

Jules Cenüs, Paris, France, assignor to Ivan Gromoff, Boulogne-sur-Seine, France

Application January 12, 1933, Serial No. 651,322

7 Claims. (Cl. 101—93)

This invention has for its object a music printing machine.

Printing music by hand is a long and complicated operation necessitating the cooperation of experienced and very skillful operators. In fact, this work presents difficulties partly caused by the fact that musical signs are of great variety in form and are not aligned as the letters of a text on one and the same horizontal line, but are distributed on the lines constituting the stave or extend beyond this stave sometimes above the latter and sometimes below the same.

Another difficulty of this work arises from the fact that the distance between two musical signs is not always the same and depends on the value of the note and on the number of signs it is necessary to insert in a bar of the musical text.

The music printing machine forming the subject-matter of the invention, by which the printing of music is made very easy and allows this work to be rapidly executed by unskilled operators, is mainly characterized by the fact that it comprises a table on which can move a frame carrying the paper on which the printing of music is to be effected, a carriage movable relatively to the table and carrying punches on which the different music characters are secured, which carriage can be moved by the operator so as to bring the punch carrying the character to be printed in front of a jointed lever actuated by a driving mechanism; a source of light provided with a suitable optical system producing a light ray is arranged on the table so that the light ray produced strikes the paper, by passing through an opening provided in the table and having a glass plate, and materializes the point where the punch, acted upon by the lever, strikes the paper, this allowing adjustment of the frame in the required position and the printing of the sign at the suitable place.

The invention is further characterized by the following arrangements:

(1) the jointed lever, acting on the punches carrying the type, is subjected to the action of a cam which imparts two downward movements to the said lever; during one of these movements, the type carried by the punch on which the lever acts, comes in contact with a small movable inked table, subjected to the action of a lever, the movements of which take place in synchronism with those of the jointed lever acting on the punches carrying the type; during the other of the said movements, the type carried by the punch comes in contact with the paper and prints it, the inked table being moved away during this time;

(2) a pedal actuated by the operator allows a clutch to connect a suitable motor to the mechanism driving the punches and the inking device

for printing each type, each depression of the pedal producing the printing of a type;

(3) the carriage carrying the type is provided with a rack meshing with a toothed wheel which can be actuated by the operator by means of a handle, in order to move the punch carrying the suitable type in the plane in which the jointed lever moves.

In order that the invention may be clearly understood, an embodiment of the same is described hereinafter, by way of example only, with reference to the accompanying drawings, in which:

Fig. 1 is an elevation, partly in section, of a music punching machine.

Fig. 2 is a plan view.

Fig. 3 is a partial elevation, partly in section, on an enlarged scale.

Fig. 4 is a partial plan view, partly in section, on the same scale as Fig. 3.

The music printing machine illustrated in the accompanying drawings, comprises: a table 1, carried by a frame 2 on which are secured a motor 3 producing the motive power, a box-like frame 4 enclosing the driving mechanism for the punches 5 and the inking table 6, and supporting the carriage 7 carrying the punches, a mechanism for driving the carriage 7, and a frame 8 carrying the paper with its guide device.

The frame 2 has an inclined face on which the table 1 is secured. Under the table 1 is attached a bracket 9 carrying a lamp 10 and an optical system 11 concentrating the light rays emitted by the lamp in a bundle of very small diameter; an opening 12 formed in the table allows the passage of this bundle, and a glass plate 13 supports the paper 14 at this opening 12.

The carriage 7, which moves on rollers 15 carried by the box-like frame 4, carries the punches 5 at the lower end of which the type 16 are respectively secured. Each punch 5 is constantly subjected to the action of a spring 17 tending to lift it. On the carriage 7 is secured a rack 18 meshing with a toothed wheel 19 keyed on one end of a shaft 20 carrying, at its other end, another toothed wheel 21 meshing with a pinion 22 driven by a crank 23. The toothed wheels 19, 21, the toothed pinion 22 and the rack 18 are so chosen that for one half revolution of the crank 23 the carriage 7 progresses in one direction or the other according to a distance equal to that separating the axes of pairs of punches.

The motor 3 drives a speed reducing device 24 which transmits the movement to a shaft 25. A clutch 26 (of the type used in cutting out or flanging presses), which is actuated by a lever 27 to one end of which is pivotally connected a link 28 rigid with a pedal 29; allows the shaft 25 to be rendered rigid with a shaft 30. A spring 31 acts on the pedal 29 and constantly tends to raise it; in the raised position, the shafts 25

and 30 are no longer rigid and do not rotate together. The shaft 30 extends within the box-like frame 4 and carries a toothed wheel 32 and a cam 33. The toothed wheel 32 meshes with another toothed wheel 34 mounted on a shaft 35, which carries another toothed wheel 36 and a cam 37. Finally, the toothed wheel 36 meshes with a toothed wheel 38 mounted on a shaft 39 carrying two cams 40 and 41 and an inking cylinder 42. The cam 37 acts on a roller 43 carried by a pivoted lever 44 which is keyed on a shaft 45 rotating in bearings 46.

On the shaft 45 is keyed a lever 47 on the free end of which is pivotally mounted a pawl 48 in engagement with a pawl wheel 49 driving a shaft 50 on which a cylinder 51 is mounted. This cylinder 51 is arranged in a cup 52; a small plate 53 arranged on the bottom of this cap 52, which serves as a receptacle for printing ink, leaves on the surface of the cylinder 51 only a thin film of ink.

A cylinder 54, pivoting about a shaft 55 supported by two levers 56 keyed on a shaft 57, alternately comes in contact with the cylinder 51 and with the inking cylinder 42, and transfers the ink which it collects from the cylinder 51, to the cylinder 42; this reciprocating movement being produced by a lever 58 keyed on the shaft 55 carrying on its free end a roller 59 moving on the cam 40.

A lever 60, keyed on the shaft 45, actuates the inking table 6 and imparts a reciprocating movement to the same. This table 6 is inked by a cylinder 61 rotating about a shaft 62 supported by two levers 63 keyed on a shaft 64, this cylinder 61 alternately coming in contact with the inking cylinder 42 and with the table 6, the reciprocating movement being produced by a lever 65 keyed on the shaft 64 and carrying, at its free end, a roller 66 moving on the cam 41.

A Y-shaped lever 67, pivoted, at the free ends of its two branches, on the shaft 45, carries a roller 68 which is in contact with the cam 33, and the free end of the lever 67 acts on the punches 5; a spring 69 secured at one of its ends to the lever 67, and at its other end, to the box-like frame 4, constantly maintains the roller 68 on the cam 33.

A spring 70, also secured at one of its ends to the box-like frame 4 and at its other end to the lever 44, constantly holds the roller, carried by the said lever 44, against the cam 37.

The frame 8, on which the paper 14 is secured, is pivotally mounted on one of the ends of two rod-like links 71, of equal length, which are each pivoted, at their other end, on a gusset 72, this gusset being pivotally connected to one of the ends of two other links 73, of the same length, the other end of which is also pivotally connected to the table 1. This linkage enables the frame 8 and paper 14 to be moved in any direction but always in parallelism with itself.

The paper 14 being secured on the frame 8, the light bundle, emitted by the lamp 10 and the optical system 11, strikes the paper 14 and forms a small light spot which is visible when looking on the paper from above, owing to the fact that the latter is translucent; this spot of light indicates the point of impact on the paper of the type 16 carried by the punch 5 under consideration. Consequently, the operator, by moving the frame 8, can determine the printing of a type at the desired place.

The carriage 7 is moved by acting on the crank

23, and the punch carrying the required type to be printed is brought opposite the lever 67.

For each printing of type, the operator must act on the pedal 29. Upon each depression of the pedal 29, the link 28 causes the lever 27 to pivot, this lever acting on the clutch 26, and the latter renders the shaft 30 rigid with the shaft 25 driven by the motor 3 during a revolution of the shaft 25, then the clutch 26 ceases to act.

The clutch 26 will cause the shaft 30 to again be rigid with the shaft 25 only when the operator depresses the pedal again.

For each revolution of the shaft 30, the cam 33 imparts two movements to the lever 67, the roller 68 of which rolls on the said cam; during one of these movements, the lever 67, urged by the spring 69, pivots about the shaft 45 and presses, by its free end, on the punch 5 located in its plane of oscillation, the punch 5 moves down and the type 16 it carries comes in contact with the inking table 6 which has come under the punch 5 owing to the action of the lever 65 keyed on the shaft 45; then, the punch 5 moves up again, the cam 33 acting on the lever 67 in opposition to the action of the spring 69, the inking table 6 moves away under the action of the lever 60, and, finally, the punch 5 moves down again, the lever 67 being again subjected to the action of the spring 69. The type 16 carried by the punch then effects an impression on the paper 14.

The rotation of the shaft 30 determines, owing to the gears 32, 34, 36 and 38, the rotation of the inking cylinder 42 and the rotation of the cams 40 and 41. The cams 40 and 41 producing the rocking movements of the levers 58 and 65 controlling the cylinders 54 and 61, the cylinder 54 comes in contact with the cylinder 51 receiving the ink contained in the cup 52, is covered with ink, and then comes in contact with the cylinder 42 which is thereby covered with ink.

The lever 47 carrying the pawl 48 also receives rocking movements and the pawl 48 imparts to the cylinder 51 a rotary movement during which the latter is covered with ink.

As will be easily understood, the printing of music, which is rendered very easy by means of the said machine, can be effected by unskilled operators.

What I claim as my invention and desire to secure by Letters Patent is:—

1. In a music printing machine, a table constituting a support for the paper, the said table being provided with an opening, a glass plate arranged in the said opening, means for moving the said paper in all directions in the plane of the said table, a source of light emitting light rays passing through the said opening and producing a spot of light through the said paper so as to previously locate on this paper the printing point of a chosen musical sign, and means for printing this chosen musical sign on the said paper at the place occupied by the said spot of light.

2. In a music printing machine, a table constituting a support for the paper, the said table being provided with an opening, a glass plate arranged in the said opening, means for moving the said paper in all directions in the plane of the said table, a source of light, means for concentrating the rays emitted by the said source of light, for directing them in the said opening and for producing a spot of light through the said paper so as to previously locate on this paper the printing point of the desired musical sign, type corresponding to each musical sign,

means for moving the punch carrying the musical sign chosen and for applying it on the place occupied by the said spot of light, and a motor for actuating, upon each printing of the 5 musical sign chosen, the punch carrying the said musical sign.

3. In a music printing machine, a table constituting a support for the paper, the said table being provided with an opening, a glass plate arranged in the said opening, a jointed device for maintaining the paper in parallelism to itself throughout its range of movement, a source of light, an optical system for concentrating the rays emitted by the said source of light, for directing them in the said opening and for producing a spot of light through the paper so as to previously locate on the paper the place for the printing of the desired musical sign, a movable carriage, punches carrying the musical signs 10 and movable on the said carriage so that the displacement of the latter allows to place the punch carrying the musical sign chosen in position to be actuated, a motor, and means actuated by the said motor for moving the said punch in order 15 that it should print the musical sign chosen on the paper at the place occupied by the said spot of light.

4. In a music printing machine, a table constituting a support for the paper and provided 20 with an opening, a glass plate arranged in the said opening, a jointed device for maintaining the paper in parallelism to itself throughout its range of movement, a source of light, an optical system for concentrating the rays emitted by the said 25 source of light, for directing them in the said opening and for producing a spot of light through the paper, so as to previously locate on the paper the printing point of the desired musical sign, a movable carriage, slides carried by the said carriage, a frame secured on the said table, rollers secured on the said frame and serving as a guide 30 for the said carriage, punches carrying the musical signs and vertically movable on this carriage, a motor, means actuated by the said motor for 35 moving the said punch for causing it to print the musical sign chosen, inking means for inking the desired musical sign, means for actuating this inking means in synchronism with the movements of the punch carrying the musical sign 40 chosen, means for kinematically and momentarily throwing the said motor in gear, and means for moving the punch carrying the desired musical sign.

5. In a music printing machine, a table constituting a support for the table and provided 45 with an opening, a glass plate arranged in the said opening, a jointed device for maintaining the paper in parallelism to itself throughout its range of movement, a source of light, an optical 50 system for concentrating the rays emitted by the said source of light, for directing them in the said opening and for producing a spot of light through the paper, so as to previously locate on the paper the printing point of the desired musical sign, a movable carriage sliding, through 55 slides, on rollers secured on the said frame carried by the table, punches carrying musical signs and vertically movable on the said carriage, a motor, a pivoted lever for acting on the punch carrying the musical sign chosen, a cam carried by a shaft for imparting a double movement to the said pivoted lever, an inking table 60

for inking the desired musical sign, a pivoted lever for moving the said inking table in synchronism with the movements of the punch carrying the musical sign chosen, a clutch for kinematically rendering the motor rigid with the said shaft, and means for actuating the said clutch.

6. In a music printing machine, a table constituting a support for the paper and provided with an opening, a glass plate arranged in the said opening, a jointed device for maintaining the paper in parallelism to itself throughout its range of movement, a source of light, an optical system for concentrating the rays emitted by the said source of light, for directing them in the said opening and for producing a spot of light through the paper, so as to previously locate on the paper the printing point of the desired musical sign, a movable carriage sliding, through slides, on rollers secured on the said frame carried by the table, punches carrying musical signs and vertically movable on the said carriage, a motor, a pivoted lever for acting on the punch carrying the musical sign chosen, an inking table, a cam carried by a shaft for imparting a double movement to the said pivoted lever, during the first movement of which the punch lowers for causing the musical sign to come in contact with the inking table which has moved thereunder, then the punch rises again, and during the second movement the punch lowers for causing the musical sign to effect an impression on the paper, the inking table having moved away, a pivoted lever keyed on a shaft for moving the said inking table, gears, a cam and a pivoted lever for imparting the movement of the first shaft to the said second shaft, an ink reservoir, rotary cylinders for transferring ink to the inking table, means causing the said cylinders to rotate, a clutch for kinematically and momentarily rendering the motor rigid with the said first shaft, and a pedal for actuating the said clutch.

7. In a music printing machine, a table constituting a support for the paper and provided with an opening, a glass plate arranged in the said opening, a jointed device for maintaining the paper in parallelism to itself throughout its range of movement, a source of light, an optical system for concentrating the rays emitted by the said source of light, for directing them in the said opening and for producing a spot of light through the paper, so as to previously locate on the paper the printing point of the desired musical sign, a movable carriage sliding, through slides, on rollers secured on the said frame carried by the table, a rack secured on the said carriage, gears for moving the said rack, a crank for controlling the said gears, punches carrying musical signs and movable on the said carriage, a motor, a pivoted lever acting on the punch carrying the musical sign chosen, a cam carried by a shaft for acting on the said pivoted lever and imparting two movements to the same, an inking table, a pivoted lever acting on the said inking table, an ink reservoir, rotary cylinders transferring ink to the inking table, a clutch for kinematically and momentarily rendering the said motor rigid with the said first shaft, and a pedal for actuating the said clutch.
